UNITED STATES PATENT OFFICE.

GEORGE FUSSNER, OF MENOMINEE, MICHIGAN, ASSIGNOR TO SIGNAL ELECTRIC MFG. CO., A CORPORATION OF MICHIGAN.

CIRCUIT INTERRUPTER.

Application filed June 18, 1920. Serial No. 389,816.

To all whom it may concern:

Be it known that I, GEORGE FUSSNER, a citizen of the Republic of Germany, and resident of Menominee, in the county of 5 Menominee and State of Michigan, have invented certain new and useful Improvements in Circuit Interrupters, of which the following is a specification.

My present invention relates to circuit 10 interrupters and with regard to the more specific features thereof to circuit-interrupters of the electro-magnetic type.

One of the objects of the invention is to provide a circuit interrupter which shall be 15 compact and durable in construction and the action of which shall be reliable and efficient.

Another object is to provide an apparatus 20 of the type mentioned, the parts of which shall be easy to produce at small expense and easy to assemble accurately.

Other objects will be in part obvious and in part pointed out hereinafter.

In the accompanying drawings in which 25 is shown one of various possible embodiments of the several features of this invention, Fig. 1 is a plan view of my interrupter in a preferred application to an electric bell, Fig. 2 is an end view of the apparatus 30 viewed from the lower end of Fig. 1, Fig. 3 is a detail view in perspective of the armature and Fig. 4 is a view in longitudinal section and on an enlarged scale taken on the line 4—4 of Fig. 1.

Referring now to the drawings, I have 35 shown my invention applied to a vibratory interrupter of the general type employed in electric bells. The bell shown comprises a base element 1 for supporting the electro- 40 magnetic parts and the gong 2. The base 1 preferably consists of a cast metal skeleton frame and includes an integral standard 3 to which are secured preferably by screws 4 a pair of electromagnetic cores 5 upon which 45 are mounted the usual electromagnetic coils 6. The armature 7 is preferably formed as an integral piece with the hammer 8, the lower part only of the latter being indicated. Secured to the armature 7 preferably 50 by screws 9 there is a flexible metal plate 10 carrying a movable interrupter contact 11 for cooperation with a stationary contact 12, a piece of insulation 13 being interposed between the armature and the 55 blade, and the screws 9 being insulated from

the blade as at 14. The stationary contact 12 is formed on the end of a contact screw 13' which is threaded between the jaws 14' of a split post 15, the jaws being clamped upon the contact screw by means of a clamping screw 16. The contact screw permits adjustment of the stationary contact.

The armature is preferably hinged at the end opposite the hammer by a novel construction now to be described. Preferably 65 integral with the end of the armature 7 are formed a pair of ears 17 and 18 bent at right angles thereto, curved at their ends as at 17' and each provided with a central perforation 19. The ears 17 and 18 are 70 fitted over a pin 20 extending into an opening 21 in the base member 1 and at right angles to said base, the said pin being firmly secured in place by means of set screw 22 which extends transversely through an opening 23 in the base. The base is preferably 75 cast with a thickened portion 24 at the region of said set screw. By preference a pair of metal washers 25 are interposed between the base portion 24 and the adjacent 80 ear 18 to provide a low-friction support for the armature.

A coil spring 26 encircles the pin 20 and has one free end 27 preferably extending upwardly through a hole 28 in a head member 29. The head member is secured upon the upper end of the pin 20 in any desired manner, as for instance, by extending the pin through an axial opening and upsetting its end as at 30 and the periphery is preferably serrated as at 31. At its other end 32 the spring is preferably extended outwardly away from the pin 20 and the extremity extends between the coil and the armature and below the head and is bent 95 toward and presses against the adjacent surface of the armature. The convolutions of the spring are preferably substantially in contact with each other and embrace the pin with small clearance, the extreme convolutions contacting the adjacent sides of the ears 17 and 18. The head 29 has a shoulder 29' adjacent the outer surface of ear 17 and the armature 7, is thus, confined against objectionable sliding along the pin 20 between washers 25 and shoulder 29'.

The terminals of the electromagnet are shown at 33 and 34 upon the same side of the casting 1 as and adjacent to the contact carrying screw 13', so that access to the 110

same and to the contacts may be readily gained from the same side, which is desirable when the device is to be inspected or repaired without removal from the wall or other fixture. The two electromagnetic coil are connected in series by the conductor 35, a conductor 36 leads from terminal 33 to one of the coils and a conductor 37 leads from the other coil to the contact screw 13', the circuit being completed through the contacts 11 and 12, the blade 10 and the conductor 38 to the second terminal 34.

It will be seen that the end 27 of the coil spring 26 is firmly held in position preferably by the head 29 upon pin 20 which in turn is firmly held in place by screw 22. If spring 26 is placed under some tension, its free end will therefore press the armature 7 away from the electromagnetic coil, thus causing the closing of contacts 11-12 as indicated on the drawings. When current is applied to the device, the electromagnetic coils are energized and attract the armature, thereby drawing the free end 32 of the spring 26 toward the left in Fig. 1 thus applying additional tension to the spring and separating contact 11 from stationary contact 12, thus breaking the circuit. The magnet becoming deenergized now, the spring 26 expands and the free end thereof pushes the armature outwardly and again closes the circuit 11-12. This operation continues while the circuit is closed with the familiar vibratory action.

For adjusting the tension of the spring 26 the set screw 22 is loosened, the head 29 is turned in the appropriate direction and through the appropriate angle either for increasing or decreasing the tension of the spring to the extent desired and the set screw is then again tightened. The up-standing end 27 of the spring preferably clears the curved end 17' of the adjacent ear 17 as shown at 40, so that no interference will occur in the process of adjustment within the ranges required in use. It will be understood that my adjustable pivot pin may be used for adjusting the tension of springs of types other than the preferred form shown.

It will be seen that my interrupter comprises few parts of simple and inexpensive construction, there being provided merely a stamped metal armature having integral hinging ears bent therefrom, a pin cut from a piece of regular stock, a coil spring made from ordinary wire, a head made from a simple stamping and a few screws. The assembly of the parts is easily effected. In my simple construction the relatively short pin 20 constitutes a rigid pivot for the armature, and since the pivoting ears that encircle the pin are integral with the armature, I dispense with the use of complex supporting devices, such as, punched or cast brackets with spe-

cially provided bearings. The construction is, thus, particularly beneficial for vibratory interrupters because of the smaller number of parts and their simple designs.

Since the spring is coiled about the pin 70 and since the deflected end is lodged between the coil and the armature and below the head, the whole length of the spring is protected against undue stretching or other distortion by tampering or otherwise. 75

Although I prefer to employ a spring of the specific type disclosed and to mount it in the manner shown and described, it will be understood that my broader claims embrace in their scope other types of springs, 80 such as pulling as distinguished from torsion coil springs.

Although I have shown my invention specifically applied to an electromagnetic interrupter of the type employed in electric 85 bells and prefer to so employ it, it will be understood that the same may be employed to advantage in vibratory regulators and in switches or interrupters generally of the non-vibratory as well as of the vibratory 90 type. 95

I claim:—

1. In electromagnetic apparatus, in combination a base, a pivot pin carried thereby and at right angles thereto, an armature in 95 a plane parallel to said pin, said armature having a pair of integral ears extending from opposite sides and near one end thereof, and at an angle to said armature, said pin extending through an opening 100 in each said ear, and a coil spring encircling said pin and having one end fixed with respect to said pin and the other in the path of movement in one direction of said armature. 105

2. In electromagnetic apparatus, in combination a support, a pivot pin mounted thereon, an armature having a pair of integral ears extending from opposite sides of said armature and at right angles thereto, said pin extending through an opening in each of said ears, and a spring coiled about said pin and disposed between said ears, said spring having one end fixed with respect to said support and the other in the 110 path of movement in one direction of said armature. 115

3. In electromagnetic apparatus, in combination a base, a pivot pin mounted thereon at right angles thereto, an armature having a pair of integral ears extending from opposite sides thereof and at right angles thereto, said pin extending across the width of said armature and through each said ear, and a helical spring coiled about said pin between 120 said ears and having convolutions in contact one with each ear, said pin having a head, one end of said spring being secured to said head and the other end resting against said armature. 125

4. In electromagnetic apparatus, in combination a base, a pivot pin mounted thereon, an armature having a pair of integral ears extending from opposite sides thereof and at right angles thereto, said pin extending across the width of said armature and through an opening in each said ear, and a helical spring coiled about said pin between said ears having successive convolutions in contact with each other, and the limiting convolutions in contact, one with each said ear, one end of said spring being secured to a part of said pin, and the other end resting against the face of said armature adjoining said pin.
5. In electromagnetic apparatus, in combination a base, a pivot pin mounted thereon and at right angles thereto, an armature having a pair of integral ears extending from opposite sides thereof and at right angles thereto, said pin extending across the width of said armature and parallel thereto and through an opening in each said ear, a spring coiled about said pin between said ears, and a shoulder on said pin preventing sliding of said armature along said pin, said spring having one end secured to said pin and the opposite end pressing against said armature.
6. In electromagnetic apparatus, in combination a support, a pin mounted thereon, an armature, a spring coiled about said pin and having one end secured thereto and the other end pressing against said armature, and means for effecting a rotary adjustment of said pin to regulate the tension of said spring.
7. In electromagnetic apparatus, in combination a base, a pivot pin mounted thereon and at right angles thereto, an armature pivoted about said pin, a spring coiled about said pin and having one end secured thereto and the other end pressing against said armature, and a set screw for securing said pin to said base.
8. In electromagnetic apparatus, in combination a base, a pivot pin mounted thereon and at right angles thereto and having a head constituting a finger piece, an armature pivoted about said pin, a spring coiled about said pin and having one end secured to said head and the other end pressing against said armature, and a set screw for securing said head against rotation.
9. In electromagnetic apparatus, in combination a base, a pivot pin mounted thereon and having an integral head constituting a finger piece, an armature pivoted about said pin, a spring coiled about said pin between said base and said head and having one end secured to said head and the other end pressing against said armature, and a set screw for securing said pin to said base.
10. In electromagnetic apparatus, in combination a base, a pivot pin mounted there-
- on, an armature in a plane parallel to said pin, said armature having a pair of integral ears extending from opposite sides and near one end thereof and at an angle to said armature, said pin extending through an opening in each said ear, a coil spring encircling said pin and having one end fixed with respect to said pin and the other in the path of movement in one direction of said armature, and a set screw for securing said pin to said base.
11. In electromagnetic apparatus, in combination, a support, a pivot pin mounted thereon, an armature having a pair of integral ears extending from opposite sides of said armature and at right angles thereto, said pin extending through an opening in each said ear, and a spring coiled about said pin and disposed between said ears, said pin having a head, one end of said spring being secured to said head and the other end pressing against said armature, and a set screw for securing said head against rotation.
12. In electromagnetic apparatus, in combination, a base, a pivot pin at right angles thereto and provided with an integral head, an armature having its width at right angles to said base, said armature having a pair of integral ears extending from opposite sides thereof and parallel to said base, said pin passing through an opening in each ear, a spring coiled about said pin between said ears, one end of said spring being secured to said head and the other resting against said armature, and a set screw securing said pin to said base.
13. In electromagnetic apparatus, in combination, a base, a pivot pin at right angles thereto and provided with an integral head, an armature extending in a plane parallel to said pin, said armature having a pair of integral ears extending from opposite sides and near one end thereof and at right angles thereto, said pin passing through an opening in each ear, said head having a shoulder resting against the adjacent ear, a spring coiled about said pin between said ears, one end of said spring fitting into a recess in said head, the other end of said spring pressing against said armature, and a set screw securing said pin to said base.
14. In electromagnetic apparatus, in combination, a base, a pivot pin mounted thereon at right angles thereto, said pin being manually adjustable about its axis, an armature pivoted about said pin, a spring having one part pressing against said armature and another movable with said pin as the latter is adjusted, and a set screw for securing said pin to said base in any position of adjustment.

Signed at Menominee in the county of Menominee and State of Michigan this 14th day of June, 1920.

GEORGE FUSSNER.
